UNITED STATES PATENT OFFICE.

BESS F. DICK, OF TOPEKA, KANSAS.

EMBROIDERY-HOOP.

1,232,242.

Specification of Letters Patent.

Patented July 3, 1917.

Application filed May 23, 1913. Serial No. 769,491.

To all whom it may concern:

Be it known that I, BESS F. DICK, a citizen of the United States, residing at Topeka, in the county of Shawnee and State of Kansas, 5 have invented new and useful Improvements in Embroidery-Hoops, of which the following is a specification.

This invention relates to work holders and more particularly to that class known as 10 embroidery hoops.

The object of the invention is principally to provide a simple and efficient device of this character which may be adjusted to different sizes whereby the hoops may be used 15 to embroider figures of large or small dimensions, the inner hoop being so constructed as to permit of its free expansion and being frictionally held in adjusted position whereby it may be conveniently released 20 from the exterior or outer hoop when desired.

Further objects of the invention will appear as the following description is read in connection with the accompanying drawing 25 which forms a part of this application, and in which:—

Figure 1 is a perspective view showing the rings connected in operative position.

Fig. 2 is a perspective view of the outer 30 ring.

Fig. 3 is a perspective view of the inner ring.

Fig. 4 is a section taken through the outer ring showing the manner of holding the ring 35 at a given diameter.

Referring more particularly to the drawing, the outer hoop consists of a band of resilient metal having one terminal thereof provided with a laterally extended stud 2 40 adapted to engage the apertures 3 formed throughout the major portion of the length of the band. The opposite terminal of the band is provided with laterally extended ears 4 which are bent inwardly over the 45 band, as shown, the terminal having the stud being arranged upon the inside of the hoop, while the terminal with the ears 4 is arranged upon the outside of the hoop

with the ears turned inwardly. The inner hoop consists of a band of spring metal 5 50 having the inner terminal provided with laterally extending ears 6 which lap over the band while the outer terminal 7 is provided with inwardly turned ears 8 also lapping over the band, as shown. 55

It will be noticed that the outer band is locked in adjusted position by the stud engaging one of the apertures while the inner band is freely adjustable, thus making it possible for the inner hoop to be expanded 60 within the outer hoop so as to hold the embroidery therebetween. At the present time when these hoops are loose and do not closely fit each other they are wrapped with cotton or some other fabric so as to make them fit 65 tightly together. This device obviates that necessity and while permitting of a wide range of adjustment also insures a tight engagement between the inner and outer hoops at all times. Furthermore, when the embroidery is put over the inner hoop and the outer hoop slipped over the same it is not necessary to stretch the fabric or pull it between the hoops, as the expansion of the inner hoop will automatically tighten the fabric over the hoop and at the same time securely grip the same between the hoops. 70

What is claimed is:—

An embroidery work holder comprising split outer and inner resilient hoops, said outer hoop being circumferentially adjustable, means for locking said hoop at different diameters, said inner hoop being constructed from a single resilient strip of material having its terminals frictionally and 80 slidably mounted upon the body portion of the hoop and said inner hoop normally tending to expand within the outer hoop to accommodate itself to the latter, and acting to hold the locking means of the outer hoop in 85 operative position. 90

In testimony whereof I affix my signature in presence of two witnesses.

BESS F. DICK.
